(57) **CLAIM**

The ornamental design for a fishing rod handle, as shown and described.

DESCRIPTION

FIG. 1 is a top perspective view of a fishing rod handle showing the new design;

FIG. 2 is a front view thereof;

FIG. 3 is a rear view thereof;

FIG. 4 is a top view, the bottom view being the same image thereof;

FIG. 5 is a bottom view thereof;

FIG. 6 is a right side view, the left side view being the same image thereof; and,

FIG. 7 is a top perspective view thereof of the design shown in the context in which it is intended to be used, the dashed lines form no part of the claimed design.
